James Mathews June 21st 1836

45

(The plaintiff referred to in this patent, and the
husband of the same, containing a description in the words
of the said James Mathews himself (of his improvement)
in the following chest.)

Be it known that I James Mathews of the city of New
York, in the State of New York have made and constructed the improvement
shown in the following chest for preserving books, papers &c.
called "Mathews' preserving chest," which is described as follows:
Required to be made of the wood and drawing of the same, man-
ning part of the application.

This chest or box consists of two doors A & B: the interior
of A holds the papers & books of sheet, size and placed
vertically from the bottom, also made of sheet iron
the same side: the space between them being filled with a compo-
sition of the composition parts of which are described below
Cement, lime, glue - The interior door B is closed
by the door A, which will sheet iron & containing the same
composition. The outer door D is also made of sheet iron
and contains the composition before mentioned. The outer
door is closed tightly upon the interior door
& represents in the drawing.

This chest is provided with double cast iron rollers
and handles for moving it from place to place.

That it claims to my invention as described in
the before described method of constructing said preserving chest
for preserving books, papers & other articles.
